UNITED STATES PATENT OFFICE

132,370

DESIGN FOR A COMBINED FAN MOTOR HOUSING AND SUPPORT THEREFOR

Harry L. Laylon, Rochester, N. Y., assignor to
Samson United Corporation, Rochester, N. Y.

Application September 17, 1941, Serial No. 103,384

Term of patent 14 years

To all whom it may concern:

Be it known that I, Harry L. Laylon, a citizen of the United States, residing at Rochester, in the county of Monroe and State of New York, have invented a new, original, and ornamental Design for a Combined Fan Motor Housing and Support Therefor, of which the following is a specification, reference being had to the accompanying drawing, forming a part thereof.

Figure 1 is a front elevational view of the combined fan motor housing and support therefor, showing my new design.

Figure 2 is a side elevational view thereof.

Figure 3 is a rear elevational view thereof.

I claim:

The ornamental design for a combined fan motor housing and support therefor, as shown.

HARRY L. LAYLON.
